UNITED STATES PATENT OFFICE.

JOHN C. McMURRAY, OF EAST BOSTON, MASSACHUSETTS.

SAFETY OIL-GAGE FOR INTERNAL-COMBUSTION ENGINES.

1,221,812.

Specification of Letters Patent.

Patented Apr. 3, 1917.

Application filed March 18, 1916. Serial No. 85,195.

To all whom it may concern:

Be it known that I, JOHN C. McMURRAY, a citizen of the United States, and resident of East Boston, county of Suffolk, State of Massachusetts, have invented an Improvement in Safety Oil-Gages for Internal-Combustion Engines, of which the following description, in connection with the accompanying drawing, is a specification, like characters on the drawing representing like parts.

This invention relates to improvements in automatic safety oil gages for internal combustion engines and is particularly adapted 15 for use in the type of engines which are used in automobiles, motor boats, etc., in which the lubrication of the wrist pins of the crank shafts, the transmission, etc., is effected by the splash system and in which it 20 necessary that the oil in the receptacle shall not be exhausted below a predetermined level.

In the usual types of engines the oil for lubricating the engine is contained in the 25 crank case and in such instances it is important that the depth of oil in the case shall be such as to permit the wrist pin of each crank to enter the oil as it reaches the downward limit of its stroke. If the oil in the 30 receptacle becomes exhausted or undesirably low the parts of the engine will not be properly lubricated, resulting in undue wear and injury to the mechanism.

The object of the present invention is to 35 provide a simple and effective device which may be readily attached to the crank case of an automobile engine or to the reservoir of any lubricating system used in connection with an internal combustion engine and 40 which will automatically signal continuously when the level of oil falls below a certain point and which will finally interrupt the ignition circuit of the engine so as to stop the engine before the oil in the crank 45 case or reservoir has become so nearly exhausted as to permit undue wear upon the parts of the engine.

Another object of the invention is to provide a device of this character with means 50 whereby the level of the oil in the crank case can be seen so that in supplying oil to the crank case a proper amount may be furnished and waste avoided.

Other objects of the invention will more 55 fully appear from the following description

and the accompanying drawings, and will be pointed out in the appended claims.

Figure 1 is a diagrammatic end view of an engine crank case and cylinder showing a preferred embodiment of my invention attached to the crank case.

Fig. 2 is a plan view of an auxiliary receptacle adapted to be attached to the crank case and which contains the regulating mechanism comprising my invention,

Fig. 3 is a vertical longitudinal central sectional view of the same, and,

Fig. 4 is a vertical median transverse central view of the same.

The invention is illustrated in the drawings as applied to a usual type of engine of which the crank shaft 1 and the crank case 2 are shown, together with the engine cylinders 3 in proper relation thereto.

The crank case 2 is usually constructed in two superposed sections, said sections having respectively flanges 4 and 5 which are secured together by bolts 6. Oil is maintained to a suitable depth in the crank case and this depth is ordinarily indicated by 80 two or more pet cocks located in suitable apertures 7 and 8 in the side or side and bottom of the crank case.

In filling the crank case the oil is supplied until it begins to run from the uppermost 85 pet cock whereupon the supply is shut off. In order to determine the height of oil afterward, the pet cocks are successively opened from the uppermost downwardly until the oil flowing from a pet cock, indicates that 90 it is below the level of the oil.

These pet cocks are located at a place which is not very convenient of access and the difficulty in thus determining the level of the oil frequently causes a careless engineer to permit his engine to run dry and thereby damage it.

By the present invention means are provided whereby, first the level of oil may be determined so that the reservoir will be filled 100 to the proper height, second, as the oil becomes exhausted a signal light located within the vision of the operator will be shown, and finally if no attention is paid to the signal thus given the engine will be 105 stopped automatically before injury to the bearings can occur.

A preferred form of the invention disclosed herein comprises an auxiliary reservoir or float chamber consisting of two com-

plementary hollow casing members 10, 11 having laterally extending flanges 10^x and 11^x adapted to be secured together by screws, bolts or other suitable fasteners. The member 10 is provided with laterally extending bosses 12, 13 having screw threaded internal apertures adapted to be connected by suitable pipes 14, 15 to the holes 7 and 8 in which the pet cocks above described are usually seated. The conductors 14, 15 are preferably of soft copper which may easily be bent so that the device may be fitted to any usual type of crank case.

The boss 12 may also be provided with an aperture having a screw threaded wall 16 to which the lower end of the supporting rod 17 may be secured, the upper end of said rod 17 being passed through one of the bolt holes in flanges 4, 5 and secured thereto by set nuts 18, 19 on said rod and abutting opposite sides of said flanges 4, 5. The other half 11 of the receptacle may be provided conveniently with an extension or boss 20 having an annular seat 21 adapted to support a gage glass 22. The gage glass 22 may conveniently be secured in the seat 21 by a cap plate 23 having a bolt 24 extending downwardly therethrough, its screw threaded lower end engaging the complementary screw threaded wall of an aperture centrally disposed in said boss 20. A shield 25 may be provided to protect the front and rear sides of the gage glass 22 and may conveniently be supported by upper and lower flanges engaged by the clamping nuts of the bolt 24.

The casing members 10 and 11 are desirably provided with oppositely disposed inwardly extending lugs 26, 27 apertured to form bearings for a pivot 28 having an arm 29 to which a float 30 may be secured by screws 31 or other suitable fastenings.

The float preferably is made of oil soaked pine or other light material of the desirable specific gravity. The arm 29 is provided at its opposite end with an extension 32 adapted to form, when the float is depressed, an electric contact with the sharp end 33 of a contact member or terminal 34 which is seated in an insulated bearing 35 which is embraced by the walls of complementary recesses in the halves 10, 11 of the casing. The upper end of the terminal 34 is provided with the usual nuts 36, 37 adapted to clamp upon a conductor 38 in the circuit of the ignition system.

A second similar terminal 39 may also be provided for controlling a signal light. This terminal may likewise be mounted in an insulating casing 40 and may have a sharp contacting member 41 extending into the float chamber. The outer end of the terminal 39 is provided with nuts 42, 43 adapted to be clamped upon the conductor 44 leading to the signal circuit.

The current through the terminal 39 of the signal circuit may conveniently be controlled by a lever 45 connected to a stud 46 mounted in bosses 47 depending from the upper walls of the casing members 10 and 11, the lever 45 being provided with a weight 49 which is adapted to maintain the end of the same in contact with the arm 29 of the float 30.

The opposite end 50 of the lever 45 is positioned to contact with the sharp end 41 of the terminal 39 when the float becomes sufficiently depressed, and before the contact member 32 engages the end 33 of the terminal 34 which leads to the ignition circuit.

As before stated the terminals 34 and 39 are respectively in the circuits leading to the magneto 51 or the ignition system and to a light circuit 52 which is diagrammatically illustrated in Fig. 3, the opposite terminals of the circuit being grounded by being connected to the frame of the machine.

It has been found difficult to control these circuits in devices of this character by reason of the fact that the contact members 90 are usually covered with oil which has a high resistance to the passage of the electric current. I have therefore connected the metallic casing with the arm 29 of the float by a flexible wire 53 and have likewise connected the arm 45 with the casing by a similar wire 54 so that the electric circuit through these members will be complete even though a film of oil be formed around the bearing of the pivots 28 and 46.

In the operation of the device the receptacle is attached in the manner above described to the apertures 7 and 8 in the crank case from which the usual pet cocks have been removed. Oil is supplied until it shows the proper height in the gage 22, the crank case being at that time properly filled.

When the engine is in use the supply of oil will gradually diminish and after it has diminished below a certain level the float will begin to fall. When the float has fallen to a predetermined point the arm 50 of the lever 45 will engage the terminal 39 of the signaling circuit and will complete this circuit so that a light conveniently located within the vision of the operator, as upon the dash or front portion of the machine will signal that the oil is getting low. Upon further exhaustion of the oil in the crank case the float in the auxiliary receptacle will be lowered so that eventually the end 32 of the float arm 29 will engage the sharp end 33 of the terminal 34 thereby connecting the same into the ignition circuit and short circuiting it or performing such other function as the change in circuit by this loop is intended to accomplish.

The ends of the terminals 34 and 39 which extend into the float chamber are preferably knife edges or points and since these ends

are engaged by conductors upon which the float 30 and the weight 49 have relatively long leverage any oil film between the contacting members is easily excluded so that a perfect contact is obtained and the operativeness of the signaling device and controller is insured.

While I have thus described a preferred embodiment of my invention it will be readily understood that it may be constructed in other forms within the spirit and scope of the following claims.

Having thus described my invention what I claim as new and desire to secure by Letters Patent is;

1. An automatic safety controller for an internal combustion engine having an electrical ignition system and provided with a lubricating system including an oil containing reservoir, said controller comprising an auxiliary receptacle, means for supporting the same below the normal level of the oil in said reservoir, means for permitting free communication between said reservoir and said auxiliary receptacle whereby said receptacle will be normally filled and the same level of oil maintained therein as in the reservoir when the level of the oil in the reservoir falls below the top of the auxiliary receptacle; an insulated electrical terminal for the ignition circuit having a contacting member extending into said auxiliary receptacle, a float in said receptacle, an electrically grounded lever having its long arm connected to said float and its short arm positioned to engage said terminal contacting member upon the settling of the float, whereby the ignition system of the engine will be rendered ineffective and the engine stopped when the oil in the reservoir has sunk to a predetermined level.

2. An automatic safety indicator and controller for an internal combustion engine having an electrical ignition system and provided with a lubricating system including an oil containing reservoir; said indicator and controller comprising an auxiliary receptacle adapted to be secured to said reservoir and to communicate therewith, insulated electrical terminals projecting into said receptacles, one of said terminals being connected to a signaling device and the other terminal to the ignition circuit of the engine, a float in said receptacle, means operable by said float adapted to engage the terminal of said signal circuit and thereby continuously to maintain the signal, an electrically grounded arm secured to said float and adapted upon exhaustion of oil to a predetermined level to engage the terminal of the ignition circuit and render the same ineffective.

3. An automatic safety indicator and controller for an internal combustion engine having an electrical ignition system and

provided with a crank case containing oil, said indicator and controller comprising a detachable auxiliary receptacle freely communicating with said crank case, whereby the same level of oil is maintained in said receptacle and said crank case, insulated electrical conductors connected respectively to a signaling device and to the ignition system, and having contact members extending into said receptacle, a float in said receptacle and independent electrically grounded levers operable by the settling of said float to predetermined levels, one of said levers being adapted to engage the contact member of the signaling device and thereby maintain a circuit through the signaling device and the other lever operable upon further settling of the float to engage the contact member of the terminal of the ignition system and render ineffective the ignition system.

4. An automatic safety indicator for lubricating systems of internal combustion engines comprising an auxiliary receptacle having a float chamber adapted to be positioned in communicative relation to a lubricant receptacle, said auxiliary receptacle consisting of two hollow complementary casing members having suitably insulated electrical terminals adapted to be connected in different electric circuits, a float having a pivotally mounted arm adapted operatively to engage one of said terminals and means also operable by said float when the same descends below predetermined levels adapted to engage the other terminal whereby a plurality of signals may be given as the level of the oil falls.

5. An automatic safety indicator and controller for the lubricating systems of internal combustion engines comprising an auxiliary receptacle having a float chamber adapted to be positioned in communicative relation to the lubricant receptacle, said auxiliary receptacle comprising two hollow complementary casing members, insulated electrical terminals adapted to be connected in different electric circuits clamped between the adjacent edges of said casing members said terminals having sharp ends extending into the float chamber, a float in said chamber and means operable by said float when the same descends below predetermined levels successively to engage the sharp edges of said terminals whereby a plurality of signals may be given as the level of the oil falls.

6. An automatic safety indicator for lubricating systems of internal combustion engines in which the crank case is partially filled with oil; comprising an auxiliary receptacle having a float chamber, a float therein and means operable by the falling of said float successively to operate a plurality of signals, means for adjustably sup-

- porting said auxiliary receptacle from the flanges of the crank casing and means adapted to be connected to the usual pet cock openings in said crank case to establish a free circulation of the oil from the crank case through said auxiliary receptacle.
7. An automatic safety device for lubricating systems of internal combustion engines comprising an auxiliary receptacle having a float chamber adapted to be positioned in communicative relation to a lubricant receptacle, said auxiliary reservoir consisting of two hollow complementary casing members, means for securing the same together, an insulated electrical terminal clamped between the contacting edges of said casing members, a lever pivotally mounted within said casing and having a short arm positioned to engage said terminal, and a float connected to the long arm of said lever adapted when the fluid in said reservoir is above a predetermined level to maintain the short arm of said lever out of contact with said terminal and means for connecting said lever in the circuit containing said terminal.
8. In an automatic safety controller for internal combustion engines having an electrical ignition system and provided with a lubricating system including an oil containing crank case, said controller comprising a closed receptacle having an upwardly extending gage glass and provided with means for establishing free communication with said crank case, means for supporting said auxiliary receptacle from said crank case below the normal level of the oil in said crank case whereby said oil level will appear in said gage glass, an insulated electrical terminal of the ignition circuit extending through the upper wall of said auxiliary receptacle and having a contact member within said receptacle, a lever pivotally mounted within said receptacle having a short arm adapted to coöperate with said terminal and a long arm provided with a float and means for pivotally mounting said lever whereby the oil in said auxiliary receptacle will normally maintain the short arm of the lever out of engagement with the contact member of said terminal but when the oil in said receptacle falls below a predetermined level will cause engagement of said lever with the contact member of the terminal and render the ignition circuit ineffective.
9. An automatic safety indicator for lubricating systems for internal combustion engines comprising an auxiliary receptacle having a float chamber adapted to be positioned in communicative relation with a lubricant receptacle, said auxiliary receptacle comprising two flanged hollow complementary casing members provided with oppositely disposed inwardly extending bosses, means for clamping the flanges of said complementary casing members together, an insulated electrical terminal adapted to be connected in the ignition system of the engine extending through the top of the casing in proximity to said bosses, a float lever pivotally mounted in said bosses having a short arm arranged in coöperative relation to said terminal and its long arm provided with a float and means for electrically grounding said lever.
10. An automatic safety indicator for lubricating systems of internal combustion engines in which the crank case is partially refilled with oil, comprising an auxiliary receptacle having a fluid chamber, a float therein and means operable by the falling of said float to operate a signal, means for adjustably supporting said auxiliary receptacle from the flanges of the crank casing, and means adapted to be connected to the usual pet cock opening in said crank case to establish a free circulation of oil from the crank case through said auxiliary receptacle.
- In testimony whereof, I have signed my name to this specification.

JOHN C. McMURRAY.
